COMBINED DENTAL JET CLEANSING UNIT OR THE LIKE AND RESERVOIR THEREFOR

Frederick Gordon Mackay, Tarzana, Calif., Keith M. Mullins, Fort Collins, Colo., and Allan B. Johnson, Tarzana, Calif., assignors to Aqua Tec Corporation, Fort Collins, Colo.

Filed Jan. 14, 1970, Ser. No. 20,912

Term of patent 14 years

Int. Cl. D24—03
U.S. Cl. D24—1

FIG. 1

FIG. 2

FIG. 3

FIG. 5

FIG. 4

FIG. 1 is a perspective view of a dental jet cleansing unit or the like and reservoir therefor embodying our new design;

FIG. 2 is a front elevation thereof;

FIG. 3 is a righthand side elevation thereof;

FIG. 4 is a rear elevation thereof; and

FIG. 5 is a top plan view thereof.

The left hand elevation of the unit is a mirror image of the righthand elevation of FIG. 3.

We claim:

The ornamental design for a combined dental jet cleansing unit or the like and reservoir therefor, as shown and described.
